UNITED STATES PATENT OFFICE.

ALBERT E. GRANT, OF NEW YORK, N. Y., ASSIGNOR TO CALOROIL BURNER CORPORATION, A CORPORATION OF DELAWARE.

PROCESS AND APPARATUS FOR MIXING AND BURNING OIL.

Application filed May 14, 1920. Serial No. 381,294.

To all whom it may concern:

Be it known that I, ALBERT E. GRANT, a subject of the King of Great Britain, residing at New York, in the county of New York and State of New York, have invented certain new and useful Improvements in Processes and Apparatus for Mixing and Burning Oil, of which the following is a specification.

10 This invention relates to oil burners and particularly to a method and apparatus for vaporizing and burning heavy fuel oil. The chief object of the invention is to provide a process and apparatus for supplying the mixture in constant quantity and composition so that the burner flame will be steady for a given adjustment.

15 A further object of the invention is to provide apparatus for vaporizing the oil and mixing the oil and air that will be simple and inexpensive and easily operated.

In the accompanying drawings illustrating the invention

20 Fig. 1 is a diagrammatic elevational view with parts in section of one specific embodiment of the invention.

25 Fig. 2 is a sectional view through a portion of the apparatus in the furnace.

30 Fig. 3 is a sectional view on line 3, 3 of Fig. 2.

35 Fig. 4 is a plan view of the apparatus shown in Fig. 2 and

40 Figs. 5 and 6 are sectional views of modified forms of mixing nozzles.

45 In the specific embodiment of the invention shown in Fig. 1 a furnace F is provided with the oil burner receiving an oil supply from a source such as the barrel O and the water supply from the water main M. In order to maintain a constant level for the oil supply to the burner a constant level tank L is provided between the source O and the burner; and to maintain a constant pressure on the water supply the pressure equalizing tank P is provided between the burner and the water main M.

50 The constant level tank L receives its supply of oil from the barrel O through pipe 10 in the form of a siphon which may be provided with a hand pump 11 to start the flow therethrough. To stop the flow at a certain level in tank L the barrel O is made air tight and an air supply pipe 12 is led from the top of the barrel to the desired level 1 in the tank

55 L. When the oil in tank L reaches the level 1 it will close the pipe 12 cutting off the air supply to the top of the oil in the barrel O and stopping the flow through siphon 10 so that a constant level is maintained for the oil feed to the burner. This siphon constant 60 level feed is particularly advantageous in avoiding the use of intermediate valves which some times become inoperative and leave passages open in a manner causing dangerous outflow of oil.

65 The pressure equalizing tank P comprises the tank body 21 with the reinforced concave riveted bottom 22, water outlet 23 and water intake 24. A pipe 25 leads from the water intake 24 to the regulated water intake 25' controlled by fiber washer valve 26 on rod 27 suspended from the phosphor bronze diaphragm 28 by disks 29. A spring 30 regulates the pressure on the upper face of the diaphragm 28 and moves in guide cylinder 31 and is adjusted by screw wheel 32. The diaphragm 28 is held in place by the cast iron top 33 of the tank bolted by bolts 37 onto flange 36. The brass casting 34 provides a seat for the valve 26 and is held in place in the bottom of the tank. In the operation of this equalizing tank water flows in from the water main M through intake 24 past valve 26 and into the tank. As the water enters the tank it displaces part of the air and creates a pressure which reacts on diaphragm 28 raising rod 27 and bringing valve 26 in contact with its seat. Spring 30 may be adjusted to reinforce the diaphragm 28 and regulate the amount of pressure necessary to close the valve 26. The water is drawn off through pipe line 23 lowering the pressure in tank 21 and reacting on diaphragm 28 to release valve 26 thus allowing water to enter the tank until the pressure is again sufficient to close the valve 26. This self operating pressure equalizing tank is sensitive to a few ounces of pressure and does away altogether with what is known as "creeping" in regulating valves which on the low side ordinarily gain about one tenth of any pressure rise on the high side.

70 In the apparatus of this invention the water supply is led through pipe 23 to a generator in the flame chamber 40 and there converted into steam and passed on to a jet 60 which controls the oil supply, sucking the oil from a level 1 below the jet. By having

the oil supply level constant and the pressure on the water supply constant variations in the mixture and in the size of the flame are avoided. At a given adjustment therefore the flame tends to remain constant and not to undergo continuous variation as has often been the case heretofore.

As a further aid to the maintenance of a steady flame the steam generator is placed 10 in proximity to surfaces heated intensely hot by the flame and the radiation from these surfaces tends to keep a constant rate of heating of the generator with resultant uniform supply of steam. Hitherto it has 15 been often the practice to heat the generator simply by directing the flame against it. Any reduction or deflection would then tend to build up serious variations and surges in the flame. For instance a temporary deflection of the flame by reducing 20 the heating of the generator would in turn reduce the pressure on the flame and consequently its size, this reduction would further lessen the heating of the generator with 25 still less pressure of the steam in the flame forming jet and thus serious falling off would develop at one moment and be followed by an opposite extreme at the next 30 causing unpleasant intermittent roaring of the burner and inefficient heating. In the apparatus of this invention the water supply entering one end the generator 35 by pipe 23' divides into two streams through the two legs of the generator 36 and 37 35 and out through cross pipe 38 and piping 39 to the nozzle 60 in the fire space 40 and above the generator 35.

The steam from pipe 39 enters the space 41 of the nozzle and passes around the 40 needle valve 42 and out through inner nozzle opening 43 as a jet at high velocity creating a partial vacuum in the second chamber 44. Also leading into chamber 44 is the oil passage 45 and the air passage 46 so that 45 oil and air are drawn into the mixture at a rate dependent upon the adjustment of the steam jet as determined by the setting of the needle valve 42 controlled by handle 47 through universal joint 48. The air passage 50 has a control 49 for its opening geared as at 50, 51 to the needle valve 42 so that as the needle valve is opened the air passage is also opened and vice versa.

The level 1 in the oil supply pipe 45 is 55 considerably below the opening of this pipe into the vacuum space 44 and the oil will normally recede to this level 1 whenever the steam jet stops so that extinguishing of the flame or shutting off of the steam jet 60 automatically stops the oil supply.

The steam jet in chamber 44 draws in and 65 mixes the oil and air in proper proportions and the combined steam oil and air jet issues from the nozzle 60 at high velocity as a combustible flame forming mixture.

The flame from this nozzle is directed downward at an angle against refractory material which is heated white hot and maintained in this condition so that any unconsumed particles of oil or carbon projected 70 against it by the flame blast will be completely burned up and no residue whatever will accumulate from the combustion.

In the specific embodiment shown in the drawings this refractory material is in the 75 form of a plate 54 supported in the fire pit 40 and having its edge surrounded by the channel drip pan 55 emptying into the drain 56. The flame from nozzle 60 directed against this plate is spread and deflected 80 around under the generator 35 above the plate and out at the sides and end. The generator therefore is heated by radiation from the flame and from the hot refractory material. Small temporary fluctuations 85 in the flame therefore do not have any effect upon the heat applied to the generator which heat remains constant for a given adjustment of the flame and does not vary as it would if the generator were directly subjected to the flame fluctuations. This constant supply of heat to the generator is important in attaining uniform operation since any decrease or increase in the 90 generator heat lowers or raises the steam pressure and in turn further lowers or increases the flame so that troublesome surges tend to build up and cause irregular 95 operations.

All of the elements of this apparatus combine together to maintain uniform conditions in the water, oil and steam supplies so that their interaction will be smooth and constant and any irregularity developing at 100 any point will not tend to be augmented but will be damped and made ineffective to interrupt the smooth operation and constant flame.

The flame projecting nozzle in feeding the oil and air by suction to the high velocity 110 steam jet thoroughly breaks up and mixes the oil and air with the steam giving a uniform homogeneous mixture burning with a very hot and constant colorless flame which consumes every particle of the oil. Modified 115 forms of nozzles are illustrated in Figs. 5 and 6, having different means for mixing the oil, air and steam. In Fig. 5 the steam pipe 61 discharges into the inner chamber 62 of sleeve nozzle 63 sliding in the cylinder nozzle 64. A needle valve 65 has its stem 66 swiveled at 67 in the end 68 of the cylinder 64 and the needle valve stem is threaded through the end of the sleeve 63 to adjust 120 the outflow of steam from this nozzle. The oil supply is drawn from pipe 69 and into the chamber 70 between the cylinder and sleeve nozzles and out around the central steam jet from nozzle 63 by the ejector action of this jet. The combined oil and steam jet then 125 130

issues into the mixing chamber 71 from nozzle 64 creating a partial vacuum therein and drawing air into the mixing chamber through passages 72. The adjustment of sleeve nozzle 63 by turning stem 66 simultaneously varies both the steam and the oil supplies to control the proportion of oil vapor in the steam.

In the modification shown in Fig. 6 the steam pipe 73 discharges into chamber 74 of nozzle 75 the outlet of which is regulated by needle valve 76. This nozzle 75 discharges the steam jet freely in the air and positioned in the path of the jet is the vacuum nozzle 77 through which the supply of oil is drawn. The nozzle 77 is adjustable by having its end 78 thread onto the lower portion 79 to provide a variable passage for the oil.

The mixture of air, oil and steam produced by the method of this invention gives a flame of large volume passing around the generator 35 and extending outward and upward against the fire pit walls. The generator 35 has its passages filled with a material such as silica gravel 83 to give extending heating surface and avoid the accumulation of a deposit by the boiling away of the water therein. This boiling and the interaction of the steam and water supply cause a constant grinding movement between the gravel particles which pulverizes any scale that tends to form and the scale powder is carried off and does not accumulate. The flame may be conveniently controlled by regulating the water supply to the generator as at 80 or by regulating the steam jet as at 47. The refractory plate 54 may be flanged as at 81 to serve as a priming pan wherein to pour the oil which is ignited to start the burner in operation. In the combination of this invention the door D of the furnace may be closed and the air supply drawn from the ash pit below and in Fig. 5 the burner jet forming means are all enclosed within the air passages 72 which are connected by pipe 73 to the ash pit thus giving a definite passage for the air to the burner which may be controlled in any suitable manner.

While this invention has been described in connection with specific embodiments thereof it is not confined thereto but is intended to cover such modifications as fall within the scope of the appended claims.

I claim:

1. In an oil burner a combination with a source of water supply at variable pressure, of means for equalizing said pressure and supplying water at constant pressure, a furnace, a steam generator in said furnace and receiving its water supply from said equalizing means, a flame forming means supplied with steam from said generator and an oil supply for said flame forming means, comprising means for automatically draw-

ing oil from a container when the level of the oil in said supply is lowered below a predetermined level.

2. In an oil burner a combination with a source of water supply at variable pressure, of means for equalizing said pressure and supplying water at constant pressure, comprising a pressure controlled valve, a furnace, a steam generator in said furnace and receiving its water supply from said equalizing means, a flame forming means supplied with steam from said generator and an oil supply for said flame forming means, comprising means for automatically drawing oil from a container when the level of the oil in said supply is lowered below a predetermined level.

3. In an oil burner a combination with a source of water supply at variable pressure, of means for equalizing said pressure and supplying water at constant pressure, a furnace, a steam generator in said furnace and receiving its water supply from said equalizing means, a flame forming means supplied with steam from said generator and an oil supply for said flame forming means, comprising a siphon for automatically drawing oil from a container when the level of the oil in said supply is lowered below a predetermined level.

4. In an oil burner a combination with a source of water supply at variable pressure, of means for equalizing said pressure and supplying water at constant pressure, comprising a pressure controlled valve, a furnace, a steam generator in said furnace and receiving its water supply from said equalizing means, a flame forming means supplied with steam from said generator and an oil supply for said flame forming means, comprising a siphon for automatically drawing oil from a container when the level of the oil in said supply is lowered below a predetermined level.

5. In an oil burner the combination with a steam generator having a constant pressure water supply, of a burner receiving steam from said generator and mixing it with oil and air and directing the mixture downward and at an angle against a refractory plate in proximity to said generator so that the flame from said burner will heat said refractory material and be directed outward around said generator.

6. In an oil burner the combination with a steam generator having an open space at the center, of a flame forming burner receiving steam from said generator and mixing it with oil and air and directing the flame downward at an angle from above said generator, and a refractory plate supporting said generator and receiving and spreading said flame around said generator.

7. In an oil burner the combination with a steam generator having an open space at

- the center, of a flame forming burner receiving steam from said generator and mixing it with oil and air and directing the flame downward at an angle from above said generator, and a refractory plate supporting said generator and receiving and spreading said flame around said generator, said generator having projections resting on said plate and spacing said generator therefrom.
8. In an oil burner the combination with a flame forming means, of a steam generator supplying steam thereto and in the form of a substantially U shaped casting having a single opening for water supply at one end and a double outlet for steam at the other.
9. In flame forming means for an oil burner the combination with a steam supply of an oil supply, means for forming said steam into a jet to spray said oil, air supply means for said jet, said air supply and oil supply being on opposite sides of said jet.
10. In flame forming means for an oil burner the combination with a steam supply of an oil supply, means for forming said steam into a jet to spray said oil, air supply means for said jet, said air supply and oil supply being on opposite sides of said jet, and a single control means for simultaneously adjusting the steam and air supplies.

ALBERT E. GRANT.
